UNITED STATES PATENT OFFICE

2,249,195

CARTON OPENER

Philip H. Unsinger, Fremont, Ohio

Application April 12, 1939, Serial No. 267,456

1 Claim. (Cl. 30—2)

This invention relates to cutting tools, especially of readily replaceable blade type.

This invention has utility as a holder and directing handle adapted to mount blades therein in a plurality of positions having a section of the blade only to project for cutting operations.

Referring to the drawing:

Fig. 1 is a side view of an embodiment of the invention in operative position as cutting a cardboard carton;

Fig. 2 is an elevation of the device from the right of Fig. 1.

Fig. 3 is an elevation of the device from the left of Fig. 1.

Fig. 4 is a view of the device with the plates or holder portion opened out to show the blade position therein.

Fig. 5 is a view similar to Fig. 2 in which one of the plate portions has a hinged or offset section in position for its flange to shield the blade protruding portion; and

Fig. 6 is a view similar to Fig. 3 wherein the straight or unflanged offset is hinged and can move into blade protecting position parallel thereto.

Carton 1 of cardboard, corrugated board, or other material, say as for handling bulk material such as foodstuffs, washing compounds, or other articles about home or factory, is a container normally sealed and as to which it is not desirable to rip or tear or rupture in any manner which might be hurtful to the contents or detract from desirability of retaining the container for an unused portion of the contents. The course adopted is to cut into a portion or fully about the container a short distance from a corner 2 so as to be just below the top. With the device as herein disclosed either of such methods, or a desired method as to a corner for even fractional cutting, may be effective.

To this end, hinge 3 has hinge plate portions 4, 5. From these countersunk or shallow portions are extensions. From the hinge portion 4 is triangular extension 6 terminating in an offset leaf portion 7. From the hinge portion 5, complementary to the triangular portion 6, is triangular extension 8 terminating in offset leaf portion 9 approximating equal plane with the offset 7, and coacting therewith to provide a guide. This offset 9 may be of a desired extent for clearing the thickness of a carton, say of corrugated board, and from this offset 9 is supplementary guide or flange 10.

The portions 4, 5, as countersunk, provide a 55

seat for back 11 of blade 12, say of safety razor type, which may have terminal notches 13, and a central opening 14, with which may cooperate boss 15 from the triangular extension or portion 8. In swinging these plate portions toward each other, the blade 12 has positive anchoring therein as a seat with projecting portion 16 therefrom between the guide portions 7, 9 for the desired extent to penetrate the carton for cutting parallel to the flange 10. The hinges and triangular portions thus serve as a holder and handle for shielding and mounting therein a cutting tool of efficiency.

15 This blade, as the projection portion becomes used to an extent defeating efficiency in operation, may be re-set by merely opening the plate portions and turning the blade end for end in the seat. As the plate portions are moved toward each other overhangs 17, 18, serve as snap ears 20 to retain the blade and holder in blade-retained position. In this form, the device is a single hinge holder and may be provided with openings 19 registering between the two triangular portions 6, 8, as an effective hanger therefor as on 25 a nail or hook.

In the event the tool be one to be placed in the pocket or not to be hung up, it may be desirable to shield the projecting portion 16 of the blade. This may be effectively accomplished by additional hinge 20 between the triangular extension 8 and the offset 9, thereby permitting flange 10 to swing toward the offset 7 and thus locate the projecting blade portion 16 away from wound-ing position (Fig. 5).

35 Instead of hinging this flanged offset 9, 10, there may be hinge 21 for the offset 7 so that this offset 7 may be thrown into parallelism with the projecting portion 16 of the blade and thus render it away from active position. These hinged devices 20, 21, of the normal leaf type have intermediate wing portion 22 abutting the plate side or triangle, and thus at opening position retain the guide portions 7, 9, in a common plane on opposite sides of the blade.

45 Near the remote triangle, portion or extension 8 has claw or tongue 23 to cooperate with seat or notch 24 of triangular portion 6 as a snap hook to retain the tool in closed working position.

What is claimed and it is desired to secure by
50 United States Letters Patent is:

A holder embodying a pair of plate portions, a hinge connecting the plate portions to form a seat adapted to anchor a blade having a cutting edge parallel to the axis of the hinge with the blade projecting partially from the seat between

the plate portions, said plate portions having leaves extending transversely of and at an angle to the plate portions to provide a plane extending laterally from the sides of the blade, said plane as extending toward the cutting edge having an acute angle to the direction of the axis of

the hinge, said leaves providing a guide for limiting the extent of penetration for the blade, one of said leaves having a hinge joint adjacent the blade upon which said leaf may swing to shield 5 the blade projecting portion.

PHILIP H. UNSINGER.
